Primary Examiner — Melody N Brown(74) *Attorney, Agent, or Firm* — Taft Stettinius & Hollister LLP(57) **CLAIM**

The ornamental design for a vehicle cab rear wall, as shown and described.

DESCRIPTION

FIG. 1 is a left, front perspective view of a vehicle cab rear wall showing our new design;

FIG. 2 is a left side elevational view thereof;

FIG. 3 is a right side elevational view thereof;

FIG. 4 is a rear elevational view thereof;

FIG. 5 is a front elevational view thereof; and,

FIG. 6 is a top plan view thereof.

The broken lines in FIGS. 1-6 depict unclaimed subject matter that form no part of the claimed design.
